UNITED STATES PATENT OFFICE.

HIRAM J. HALLE, OF NEW YORK, N. Y., ASSIGNOR TO UNIVERSAL OIL PRODUCTS COMPANY, OF CHICAGO, ILLINOIS, A CORPORATION OF SOUTH DAKOTA.

APPARATUS FOR TREATING PETROLEUM OIL.

Application filed September 1, 1920, Serial No. 407,329. Renewed September 18, 1926.

This invention relates to improvements in apparatus for treating petroleum oil and refers more particularly to an apparatus adapted for conversion of relatively heavy hydrocarbons into lighter or lower boiling point hydrocarbons, such as gasoline or gasoline-like bodies.

In the cracking of petroleum oil, the effective utilization of the fuel used in heating the oil to the cracking temperature is a practical problem of prime importance. In the cracking of petroleum oil under relatively high temperatures and pressures, the fuel cost is high, and this is true, even in most efficient firebox construction. The transfer of the thermal units to the oil is subject to the usual stack losses and losses by radiation. One of the objects of this invention is to reduce this fuel cost to a minimum and obtain effective heat transfer to provide an equable uniform heating of all parts of the oil instead of local high and low temperatures in different parts of the oil body. I accomplish this object by causing the gases of combustion, before they reach the stack, to pass through a heating coil or flue extending through and entirely surrounded by the oil stream under treatment. Preferably, the fuel coil or coil for the gases of combustion is internally arranged within the heating coil which carries the oil. By this method and means, I am enabled to secure, as will be seen, a most effective heat transfer, while at the same time in no way interfering with the continuous passage of the oil through the heating coil.

As a further object of the invention, effective means are provided for preventing local overheating of the tubes through which the oil passes, while at the same time, permitting of a controlled heating whereby the oil tubes may be either externally or internally heated, or both.

In the drawings:

Fig. 1 is a view, partly in vertical section, partly in side elevation, with parts shown in dotted lines.

Fig. 2 is a view on an enlarged scale, of both the oil coil and the coil for gases of combustion, with parts broken away to reduce the size of the drawing.

Fig. 3 is a cross sectional view on a still larger scale.

Referring in detail to the drawings 1, des-

ignates the furnace provided with burner 2, bridge wall 3, combustion chamber or fire box 4 and stack 5. Within the combustion chamber is mounted the coil for containing the oil, designated as a whole 6, which coil comprises a series of tube 7, these tubes being connected at their ends by the headers 8 and flanges 9 and 10. The arrangement is such that the oil enters the charging line 11 and after passing through the coil, discharges into the vapor chamber 12 through the transfer line 13. The vapor chamber 12 is preferably located outside of the fire box as shown and may take the form of a cylinder of relatively large diameter.

The charging stock may be continuously fed to the oil coil by a pump (not shown) connected to any suitable source of supply. Vapors pass out of the upper part of the vapor chamber through gooseneck 14 to a reflux condenser 15, the upper part of which is connected by a line 16 to water condenser 17 seated in condenser box 18. The condenser coil 17 is connected to receiver 19, which receiver is provided with liquid level gauge 20 and pressure gauge 21. The receiver is also provided with liquid drawoff pipe 22, controlled by throttle valve 23 and gas outlet 24, controlled by valve 25. Throttle valves 26 and 27 may be interposed in the lines 14 and 16 respectively as shown, and similarly, a throttle valve 28 may be interposed in the transfer line 13. The vapor chamber is also provided with residue drawoff pipe 29, controlled by throttle valve 30.

Describing now more particularly the manner of heating the oil, it will be noted that the gases of combustion may pass externally around the oil heating coil and thence into the common flue 31. The passage of the gases from the flue 31 to the stack 5 is controlled by a manually operated damper 32. As a novel feature of the invention, the gases of combustion can also pass through the flue coil 33, which extends internally through the oil coil 6. Referring more particularly to Figs. 2 and 3, this coil 33 takes the form of relatively smaller pipes or tubes 34, which are connected through the headers 8 by means of the elbows 35 and unions 36. The inlet end of the coil 33 is connected by pipe 37 to the main flue 31. A manually controlled damper 38 is inter-

posed in the pipe 37. The gases of combustion, after passing through the coil 33 are delivered to the stack 5 by means of the discharge pipe 39. A manually controlled damper 40 is interposed in the pipe 39.

It will be noted that there are two banks of the oil heating coils and there are similarly two banks of the flue coils. The internal diameter of the tubes forming the oil coil is somewhat larger than the external diameter of the flue coil so as to permit of a relatively shallow stream of oil passing freely through the outer or larger tubes.

15 The internal tubes are arranged concentric of the outer ones and separated therefrom by means of the lugs 41, these lugs 41 preferably extending spirally around the inner tubes so as to more effectively brace the 20 structure, and to cause a mixing action, so as to expose all the particles of oil to a uniform heat and cracking action.

By means of the foregoing construction, I can simultaneously, both externally and 25 internally, heat the stream of oil passing through the heating tubes and by closing the damper 32, I can compel all the products of combustion to pass through the flue coil 33 or by partial closing thereof I can compel 30 a part of these gases to pass therethrough. Similarly, by regulating the dampers 38 and 40, I can control the passage of gases of combustion through the coil 33. The oil under treatment may be maintained under 35 a uniform vapor pressure throughout the system of 100 pounds to the square inch and the reflux condensate drawn off from the bottom of the reflux condenser 15 through the pipe 15', controlled by throttle valve 15'' 40 and sent back either to the charging line or to any other suitable receptacle where it may be further treated as desired. If desired, a differential pressure may be main-

tained upon the system by suitably regulating the valves shown.

The most important feature of the invention, however, lies in the manner of heating the oil and it may be noted that the flow of the gases of combustion through the internal heating coil may be readily controlled and varied as the process continues. However, care should be taken at all times to keep the oil in liquid phase in the oil tubes so as to prevent carbon in these tubes precipitating, with constant clogging up or 55 injury to the tubes.

I claim as my invention:

1. In an apparatus for cracking petroleum oil, the combination with a coil located in a furnace through which oil is continuously passed, of a second coil disposed within said oil coil forming an annular oil passageway, spirally arranged spacing lugs carried by said second coil, to space the same from the oil coil and act as baffles for the oil passing through said annular passageway, a flue leading from the furnace, means for withdrawing heated gases from said flue to be passed through said second coil to internally heat the oil passing through said annular passageway.

2. In an apparatus for cracking petroleum oil, the combination with a coil located in a furnace through which oil is continuously passed, of a second coil disposed within said oil coil forming an annular oil passageway, spirally arranged elements mounted between the two coils to space the two coils from each other and act as baffles for the oil passing through said annular passageway, a flue leading from the furnace, means for withdrawing heated gases from the furnace to be passed through said second coil to internally heat the oil passing through said annular passageway.

HIRAM J. HALLE.
